UNITED STATES PATENT OFFICE.

WARREN H. CLARK, OF WEST BURLINGTON, NEW YORK.

BALL.

1,421,407.

Specification of Letters Patent.

Patented July 4, 1922.

Application filed July 25, 1921. Serial No. 487,298.

To all whom it may concern:

Be it known that I, WARREN H. CLARK, a citizen of the United States, residing at West Burlington, in the county of Otsego 5 and State of New York, have invented a new and useful Ball, of which the following is a specification.

This invention relates to rubber balls, the object of the invention being to provide a 10 ball which may be used as a hand ball, novel means being provided for housing the elastic elements which connects the ball and the button used in connection therewith.

With the foregoing and other objects in 15 view which will appear as the description proceeds, the invention resides in the combination and arrangement of parts and in the details of construction hereinafter described and claimed, it being understood 20 that changes in the precise embodiment of the invention herein disclosed and claimed, may be made within the scope of what is claimed, without departing from the spirit of the invention.

25 Referring to the drawing:—

Figure 1 is a side elevational view of a ball constructed in accordance with the present invention.

Figure 2 is a sectional view through the 30 ball disclosing the means of housing the flexible member and button.

Referring to the drawing in detail, the reference character 5 designates the ball which is of the usual construction, the same 35 being hollow to cause the ball to rebound when the same is thrown against a rigid object.

A flexible member indicated at 6 has connection with the ball in any suitable manner, the opposite end of the flexible member having connection with the button 7 which is adapted to be positioned between adjacent fingers of the hand of an operator, whereby 40 the ball may be thrown, the elastic member 6 returning the ball to the hand of the user.

Associated with the ball 5 is a semi-spherical rubber cover 8 which possesses such elastic qualities as to cause the same 45 to firmly grip the ball 5 and secure the same thereto.

This cover 8 is provided with a circular opening to accommodate the button 7, the outer surface of the button being shown as curved, to conform to the contour of the surface of the ball.

When the button and the elastic member 6 are out of use, a depressed portion is made in the ball proper, in which depressed portion is positioned the elastic member 6. The cover 8 is now positioned over the ball 60 as illustrated by Figure 2 of the drawing, and the button 7 positioned in the opening thereof.

Having thus described the invention, what is claimed as new is:—

1. A hollow ball formed of resilient material, a semi-spherical member having an opening, and adapted to be positioned over the ball, a flexible member having connection with the ball and carrying a button, 70 and said button adapted to be positioned in the opening of the semi-spherical member.

2. A hollow ball formed of resilient material, a flexible member having connection with the hollow ball, said ball adapted 75 to be depressed to form a cavity to receive the flexible member, a semi-spherical member adapted to be positioned over the ball to secure the flexible member within the cavity, and a button carried by the flexible 80 member.

3. A hollow ball formed of resilient material, said ball having a depressed portion, a flexible member having connection with the ball and adapted to be positioned 85 within the depressed portion, a cover for securing the flexible member within the depressed portion, said cover having an opening, a button carried by the flexible member and adapted to be positioned in the open- 90 ing, and said opening having a curved surface to conform to the curvature of the cover.

In testimony that I claim the foregoing as my own, I have hereto affixed my signature in the presence of two witnesses.

WARREN H. CLARK.

Witnesses:

CLARENCE W. HORTON,
C. E. QUACKENBUSH.
